UNITED STATES PATENT OFFICE.

KARL GRAMM, OF BERLIN, GERMANY.

PETROLEUM-MOTOR ENGINE.

SPECIFICATION forming part of Letters Patent No. 415,908, dated November 26, 1889.

Application filed June 25, 1889. Serial No. 315,479. (No model.)

To all whom it may concern:

Be it known that I, KARL GRAMM, a subject of the King of Prussia, residing at Berlin, in the Kingdom of Prussia, Germany, have 5 invented new and useful Improvements in Petroleum-Motor Engines, of which the following is a specification.

This invention relates to petroleum-motor engines, and has for its object to provide an 10 apparatus by means of which the explosive mixture is produced and introduced into the cylinder of the engine by causing a jet of air to take up a certain quantity of petroleum, which mixes therewith in the form of a spray, 15 the mixture being then carried into the heated cylinder.

The invention is carried out by means of the apparatus illustrated in the accompanying drawings.

20 The air-jet is produced by means of a small air-pump A, driven by the engine, and passes from the valve-chamber B, through valve D, into the chamber of the cylinder situated behind the valve II, where, by the sucking action 25 of the air-jet, the petroleum is drawn out of the vessel G, through the pipe f, and, mixing with the air in the form of spray, passes with the same and with a further body of air into the vaporizing-chamber of the cylinder.

30 Figure 1 shows diagrammatically a vertical section through the complete apparatus. Figs. 2 and 3 show the construction of air-pump employed in elevation and vertical section, on an enlarged scale.

35 The compressing-pump A is constructed as a pump without valves, the pump-cylinder C' being mounted on a fixed pivot at Q, so as to have an oscillating motion imparted to it by the piston or plunger as this is reciprocated 40 by a crank driven by the engine. On the side of the cylinder is formed a flat face R, against which is pressed air-tight a head S, fixed on the end of a pipe V. From the bottom of the cylinder a passage T leads to a 45 port U in the face R. Assuming the crank to be rotating in the direction of the arrow, Fig. 2, the piston during its upward or suction stroke will move the cylinder from the central position shown toward the left and then back again into that position, so that during such stroke the port U will remain uncovered, and consequently the piston will

draw in air through it. On the return or compression stroke the cylinder in moving to the right of the position shown and back again will cause the port U to pass behind the head S, and consequently the air will be forced by the piston through the enlarged opening of S into the pipe V, the port U passing from behind the head again toward the end of the stroke. The head S being pressed air-tight against the face R by a spring, the compressed air in the pipe V cannot escape when the cylinder is performing the first-described semi-oscillation. A volume of compressed air being thus maintained by the pump in the chamber B, with which the pipe V communicates, a portion thereof is allowed to escape by the opening of the valve D on the upstroke of the engine-piston C, which air, passing through pipe E, issues as a jet immediately over the orifice of the petroleum-conduit f, situated at right angles thereto, and, as before described, draws a certain quantity of petroleum out and carries it with it in the form of spray, together with a further quantity of air drawn in through the pipe L, past the valve H in the valve-chamber H', into the cylinder-space F, thus forming a charge consisting of finely-divided petroleum spray and air, the petroleum of which becomes effectually vaporized on contact with the heated recessed bottom K of the cylinder, the charge being subsequently fired in the usual manner.

In order to maintain a constant level of the petroleum in the vessel G, there is arranged above the same a supply-tank M, from which it is allowed to drip into G through a cock N, so as to be slightly in excess of the amount used, the surplus flowing off through the overflow-pipe O into the receptacle P.

The valves D and H are both actuated by suitable cams driven by the engine and timed so as to open them at the required moment.

Having thus described my invention, what I claim as new, and desire to secure by Letters Patent, is—

1. In a petroleum-motor engine, the combination, with the cylinder C', having vaporizing-chamber J, chamber H', opening into the vaporizing-chamber J, and having an inwardly-closing valve H, and air-discharge pipe L, the air-chamber B, with an inwardly-

opening valve D, and air-pipe E, connecting with valve-chamber H', and the air-pipe V, connecting with air-chamber B at one end and having the fixed head S at the other end, of 5 the oscillating air-pump cylinder A, having the side air-passage T, leading from one end of the cylinder and having the port U in the flat projection R, movable into and out of connection with the head S, substantially as 10 described.

2. In a petroleum-motor engine, a cylinder C', having a vaporizing-chamber J, a valve-chamber H', opening into the chamber J, with an inwardly-closing valve H, an air-discharge 15 pipe L, and air-jet pipe E, connected with an air-pump for conveying an intermittent air-jet into the valve-chamber H', in combination with the oil-reservoir G, having an over-flow-pipe O, and an oil-discharge pipe f, connecting with valve-chamber H', the drip-receptacle P, located beneath the pipe O, and the oil-reservoir M, having a cock N, located above the reservoir G, substantially as de- 20 scribed.

25 3. The combination, with the cylinder C', of a petroleum-motor engine having a vaporizing-chamber J, a valve-chamber H', opening into

the chamber J, and having an inwardly-closing valve H, and air-discharge pipe L, of an oil-reservoir G, with an overflow-pipe O, and 30 oil-discharge pipe f, connecting with the valve-chamber H', an oil-receptacle P, located beneath the pipe O, an oil-reservoir M, with cock N, located above the reservoir G, an os- 35 cillating air-pump cylinder A, having the side air-passage T leading from one end of the cylinder, and having the air-outlet port U in the flat projection R on the side of the cylinder A, and the air-chamber B, with the inlet-valve D, air-jet pipe E, connecting with 40 the valve-chamber H', and the air-pipe V, connected at one end with the air-chamber B, and at the other having the fixed head S, connecting with port U, and into and out of connection with which the port U is movable, 45 substantially as described.

In testimony whereof I have signed my name to this specification in the presence of two subscribing witnesses.

KARL GRAMM.
